UNITED STATES PATENT OFFICE.

JOHN B. HADAWAY, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

HEEL.

Original application filed July 25, 1921, Serial No. 487,314. Patent No. 1,617,049, dated February 8, 1927.
Divided and this application filed December 4, 1922. Serial No. 604,761.

This invention relates to cushion heels, and has for its object to provide an improved composite heel capable of economical and perfect attachment by machinery.

5 In the accomplishment of the object stated, I have produced a composite heel capable of attachment by machinery at a single nailing operation without the use of the cement which has heretofore been used with machine
10 attached heels. In this connection an important feature of the invention resides in the combination with a rigid base section having a flat outer face of a rubber top section having a curved inner face, the two sections being secured together in registered
15 relation by one or more nails. This mechanical combination of a curved rubber lift with a rigid base makes it practicable for the first time to attach by single nailing with the ordinary commercial heelng machines used
20 in shoe factories a heel base and a rubber lift which is sufficiently curved to produce a tight edge joint without the aid of cement, such curved rubber lifts having been heretofore attached separately by hand.

25 A further feature of the invention relates to a composite heel construction which provides for easy and exact registering of the two sections of the heel. In the illustrated
30 embodiment of the invention this is accomplished by providing the two sections of the heel respectively with registering recesses and projections of shapes which are angularly dissimilar in cross sectional contour.
35 In a convenient, practical construction the base section has circular recesses in its outer face and the rubber section has correspondingly located, frusto-pyramidal projections on its adjacent contacting face. I have
40 found it advantageous so to proportion the projections and recesses that the diagonal of the base of the projection is greater than the diameter of the recess. The yielding quality of the rubber, however, permits the
45 projection easily to be forced into the recess, the surplus yielding material being easily accommodated because the shorter cross-sectional dimension of the projection is less than the diameter of the recess. It has been
50 demonstrated in practice that the registration of the two parts of the heel is very easily and accurately accomplished, when the heel is constructed in accordance with this

invention. By forming the rubber section in the proper shape and thus registering the two parts of the heel they may be sufficiently secured together by one or more tacks or nails to permit the composite heel to be handled and the necessity for cementing the two sections together is eliminated. A novel composite heel is thus produced which has no cement between the base and rubber section, the rubber section being secured to the base only by nails.

55 The above and other features and advantages of the invention will be more clearly understood from reading the following detailed description of one embodiment thereof in connection with the accompanying drawings, in which

60 Figure 1 is a perspective view of a cushion heel made in accordance with the invention, portions being broken away to illustrate the construction and arrangement;

65 Fig. 2 is an exploded view showing the under side of the cushion heel section and the top of a base section, which have been assembled to form a composite heel and separated by breaking the assembling nails;

70 Fig. 3 is a sectional view showing the heel attached to a shoe at a single nailing, the section being taken along the line 3, 3 of Fig. 2;

75 Fig. 4 is a perspective view of the heel portion of a shoe, showing the worn rubber section removed preparatory to the attachment of a new rubber section; and

80 Fig. 5 is a view similar to Fig. 4, illustrating what occurs when it is attempted to remove an ordinary rubber heel, attached at a single nailing.

85 Referring now to the drawings, 10 indicates a rubber heel section of lift, and 12 indicates a rigid base section which may be built of leather, leatherboard or other suitable material.

90 The rubber section 10 is preferably of uniform thickness throughout and consists of a central, flat portion and a curved edge portion 14 extending around the periphery of the flat portion, with the exception of the breast edge. The heel thus constructed is, 95 in effect, concave upon its inner or contacting face and convex upon its outer or tread face but becomes flattened when it is pressed upon a shoe and, by reason of the normally inwardly curved marginal portion 14, a tight

joint around the edge is assured without the necessity of resorting to cement. On the inner face of the rubber lift are formed two frusto-pyramidal projections 16 which are shown as square in cross-section and the tops of which lie in approximately the same plane as the edge 18 formed by the intersection of the inner face of the curved periphery of the lift.

In the tread face of the lift are formed a plurality of approximately conical holes or depressions 20, arranged in a regular design and indicating or designating the nailing locations, that is to say, the places where the nails are to be driven. Washers 22 are embedded in the rubber at certain of the designated nailing locations and omitted in certain others of said locations, as will be explained in more detail hereinafter. Contrary to the usual practice the bottoms of the depressions 20 are completely closed or imperforate, there being a substantial thickness of rubber between the bottoms of those depressions which have washers in register with them and the corresponding washers, as clearly shown at 24 in Fig. 1. The necessary holes made by the washer supporting pins in the vulcanizing mold in which the heel is manufactured, which are usually to be found in the tread face of a rubber heel are, in this instance in its inner face, and by reference to Fig. 2, wherein these holes are indicated by the reference numeral 26, the locations of the washers 22 in the heel section may be readily determined, it being understood that there is such a washer in alignment with each of the said holes. By comparison of Figs. 1 and 2, it will be seen that certain of the designating depressions 20 have washers, while certain others, such as the one shown at 25 in Fig. 1, have no washers, the rubber beneath the latter being unbroken, as illustrated at 27.

In the outer face of the base section 12 are two cylindrical recesses 28 corresponding to the projections 16 on the contiguous face of the rubber section 10. The top of the pyramidal projection 16 is preferably slightly smaller in every horizontal dimension than the diameter of the recess 28 but the diagonal of the base of the projection is slightly greater than the diameter of the recess, with the result that the projection will enter the recess readily, while contact of the projection with the walls of the recess is insured and consequently accurate register of the rubber section and the base section is secured. Furthermore, the material of the projections 16 being of a yielding nature, the accuracy of the registration is practically unaffected by shrinkage or expansion of the recesses 28 due to various conditions of temper of the base section of the heel.

The sections 10 and 12 may be assembled and preliminarily attached together by two

assembling nails 30 driven through the two washers nearest the projections 16 and clinched on the under side of the base section, as shown in Figs. 2 and 3. By utilizing the particular washers nearest the projections 16 for these nails any danger of the projections being pulled out of the recesses 28 by the natural tendency of the rubber heel to spring away from the base is avoided. Such a contingency, of course, would involve danger of destroying the proper register of the two heel sections.

Assuming the composite heel to have been assembled, as above described, it is ready for attachment to a shoe. This heel is perfectly adapted for attachment by commercial heelng machinery, all the nails being driven at a single operation. The nails may be of different lengths, the longer ones being shown at 32 and the shorter ones at 34. The short nails 34 are driven through the bottoms of the cavities 25 beneath which there are no washers and are driven completely through the rubber section until their heads are seated on the outer face of the base section 12, their points being clinched in the insole 36. The longer nails 32 are driven through the washers 22 until their heads are seated in the washers and their points are also clinched in the insole. As the nails are driven they cut their way through the rubber and when the heelng machine drivers are withdrawn the rubber, in resuming its normal condition, closes over the heads of the nails, as indicated at 38, effectually and completely concealing them from view. A blind nailed rubber heel of pleasing appearance is thus secured which is suitable for the very best class of footwear.

Upon comparison of Figs. 1 and 2 it will be apparent that, in the illustrated heel, there are four of the designated nailing locations at which there are no washers, and there will, therefore, be four of the nails 34 which serve to attach the base section 12 to the outsole 40, upper 42 and insole 36 of the shoe. These nails 34, as previously stated, serve only as base attaching nails and play no part in securing the rubber section 10. The longer nails 32, the heads of which are seated in the washers, secure both the rubber section and the base and the nails 30 secure the rubber section to the base. Attaching nails are, of course, omitted from the two holes in the nailing die of the heelng machine which correspond to the previously inserted assembling nails 30.

Fig. 5 illustrates the condition which frequently results when a shoe repairer attempts to remove an ordinary rubber heel which, with the base, has been attached to a shoe at a single nailing. With such heels every nail is driven through a washer, and when the rubber heel is removed the nails

are, of course, all pulled out with it. The base 12, being attached only by the same nails, usually comes away from the heel seat of the shoe with the rubber section. It is customary then to separate the base from the worn rubber section and to nail the base upon the heel seat of the shoe before the new rubber heel is attached. It is usually impossible to reattach the base section so perfectly that the edge does not need re-finishing.

Fig. 4 illustrates the conditions which exist when the improved heel of the present invention is used. Although this heel is attached at a single nailing, with all the attendant economies, the base attaching nails remain undisturbed when the worn rubber section 10 is pried off and the attachment of the base 12 to the heel seat of the shoe is left secure, the shoe being ready for the immediate attachment of the new rubber lift.

It should be understood that the form of designation for the nailing locations may varied from the conical depressions 20, herein illustrated, without sacrificing the advantages of the invention. The important requirement is that some sort of designation or surface formation be provided which will render the marks made by the nails passing through the heel inconspicuous or unnoticeable and this may be accomplished by breaking up the smoothness of the surface of the tread face of the heel in any one of a variety of ways. Otherwise it is practically impossible to avoid defacement of the tread surface of the rubber section.

The method and machine for attaching the heel of the present invention are not claimed herein, the same being fully disclosed and claimed in United States Letters Patent No. 1,617,049, granted Feb. 8, 1927, upon an application of the present inventor, of which the present application is a division.

Having described the invention, what is claimed as new and desired to be secured by Letters Patent is:

1. A composite heel consisting of a rigid section and a yielding section in contact with each other, one of said sections having a

projection on its contacting face and the other of said sections having a recess in its contacting face, said projection engaging in said recess and the contacting portions of the projection and recess being angularly dissimilar in cross sectional contour. 55

2. A composite heel consisting of a rigid section and a yielding section, in contact with each other, one of said sections having a plurality of spaced apart projections on its contacting face, and the other of said sections having a corresponding plurality of similarly spaced recesses in its contacting face, said projections engaging in said recesses and the contacting portions of the projections and recesses being angularly dissimilar in cross sectional contour. 60

3. A composite heel consisting of a rigid section and a yielding section in contact with each other, one of said sections having a projection upon its contacting face and the other of said sections having a recess in its contacting face, said projection and recess being in register with each other and one being approximately circular in cross section 70 and the other being polygonal in cross section. 75

4. A composite heel consisting of a rigid base section and a yielding top section in contact with each other, the base section having a substantially circular recess in its contacting face, and the top section having a polygonal registering projection on its contacting face arranged to enter the recess. 80

5. A composite heel consisting of a rigid base section having a substantially circular recess in one face, and a yielding top section applied to said face and having a rectangular projection the diagonal of whose base is greater than the diameter of the circular recess, arranged to enter said recess. 85

6. An unattached cementless, composite heel consisting of a rigid base section having a flat, outer face and a rubber top section having a curved inner face, said sections being secured together in registered relation by one or more nails. 90

In testimony whereof I have signed my name to this specification.

JOHN B. HADAWAY.
